DESIGN FOR A PHONOGRAPH CABINET

David C. Rockola, Chicago, Ill., assignor to Rock-Ola Manufacturing Corporation, Chicago, Ill., a corporation of Delaware

Application October 17, 1938, Serial No. 80,508

Term of patent 14 years

To all whom it may concern:

Be it known that I, David C. Rockola, a citizen of the Dominion of Canada and a resident of Chicago, in the county of Cook and State of Illinois, have invented a new, original, and ornamental Design for a Phonograph Cabinet, of which the following is a specification, reference being had to the accompanying drawing, forming a part hereof.

The drawing shows a perspective view of a phonograph cabinet embodying my novel design, the side walls of the cabinet being identical in appearance.

I claim:

The ornamental design for a phonograph cabinet, substantially as shown and described.

DAVID C. ROCKOLA.
